UNITED STATES PATENT OFFICE.

OTTO N. WAELETTI AND EDWARD F. CHESNEY, OF SEMANS, SASKATCHEWAN, CANADA.

AUTOMOBILE-EXTRACTOR.

1,334,195.

Specification of Letters Patent. Patented Mar. 16, 1920.

Application filed June 11, 1917. Serial No. 174,160.

To all whom it may concern:

Be it known that we, OTTO N. WAELETTI and EDWARD F. CHESNEY, both citizens of Canada, residing at Semans, in the Province 5 of Saskatchewan and Dominion of Canada, have invented a new and useful Automobile-Extractor, of which the following is a specification.

This invention relates to motor vehicle 10 crabs or devices adapted for emergency purposes for application to a motor vehicle to adapt said vehicle by means of its own power to extricate itself from a mud hole or other difficult place when the driving 15 wheels of the machine are unable to obtain the necessary traction on the road surface for that purpose.

An object of the present invention is to provide a simple, strong and reliable crab 20 and cable, which crab is adapted to be firmly secured to one of the driving wheels of the vehicle in an expeditious and easy way, requiring no alteration or adjustment of any part of the motor vehicle itself. The 25 device when detached from the driving wheel may be readily carried in the tool box or one of the compartments of the machine.

With the above and other objects in view, 30 the invention consists in the novel construction, combination and arrangement of parts, as herein described, illustrated and claimed.

In the accompanying drawings,

Figure 1 is a vertical section taken trans- 35 versely through the hub of one of the driving wheels of a motor vehicle and the parts immediately adjacent thereto, showing the improved motor crab in its applied relation thereto.

Fig. 2 is an outer face view of the crab.

Fig. 3 is an inner face view thereof.

Fig. 4 is a detail view of one of the anchors or stakes.

Fig. 5 is a diagrammatic plan view illus- 45 trating the method of using the apparatus.

The motor crab comprises a cable winding drum 1 of cylindrical formation and of suitable external diameter around which is wound a flexible cable 2 which is used for 50 extricating the motor vehicle from a mired or stalled position. The drum 1 has at its outer side a flange 3 which prevents the cable 2 from working off the drum.

In connection with the drum 1, we employ 55 a circular series of spider arms 4 which also constitute guards to prevent the cable 2

from working off the drum 1. The arms 4 are inclined to give proper clearance to the outer hub plates 5 of the vehicle wheel, the wheel hub being of the usual formation and 60 comprising the hub 6 proper, the outer hub plate 5 and the inner hub plates 7, 8 designating the spokes which are clamped between the plates 5 and 7 secured by the usual bolts 9 which also serve to fasten to 65 the wheel hub the usual brake drum 10 which is disposed at the inner side of the wheel.

Each of the spider arms 4 has an outwardly extending portion 11 which is inserted through a hole extending transversely through the drum 1, said portion 11 of the spider arm also passing through an abutment ring 12 which bears against the outer side of the drum, the outer end of the portion 11 of the spider arm being threaded 70 to receive a clamping bolt 13. Each spider arm is also provided with an inwardly extending portion 14 which passes between adjacent spokes and also pass through a wedge 75 shaped spoke block 15 so that the portion 4 of each spider arm is maintained in a certain fixed relation to the spokes of the wheel.

Arranged upon the inner side of the 80 wheel are semi-circular clamping members 16 through which the portions 14 of each of the spider arms 4 are inserted and secured by means of wrench nuts 17 or nuts having operating handles 18 to facilitate 85 taking off and applying said nuts. Each of the semi-circular clamping members 16 has a cushion 19 of felt or like material, secured to the inner face thereof to bear against the spokes 8 and prevent marring 90 the finish thereof. The spoke blocks 15 are not fastened directly to the wheel but are held in place between the semi-circular clamping members 16 and the inclined 95 spider arms 4, the latter in turn bearing 100 against the outer hub plate 5 as shown in Fig. 1.

The way of using the apparatus is illustrated in Fig. 4 wherein it will be observed that, in the preferred embodiment of the 105 invention, we employ two anchors 20. One of said anchors is illustrated in Fig. 4, wherein it is seen to comprise two arms or legs 21 and 22 connected together at one end by means of a pivot 23, which may be 110 removable, if so desired, in order that the parts of the anchor may be more compactly

stored in a compartment or tool box of the motor vehicle. The arm 21 has a long tapering point adapting it to be driven into the road surface, while the other arm 22 is provided adjacent to the pointed extremity thereof with an inclined offset extension foot 24 which serves to limit the penetration of the arm 22 into the road surface by resting on the road surface. This prevents the tilting of the anchor when stress is brought to bear thereon by the cable 2. The rear ends of the cable 2 are securely fastened to and wrapped around the drums 1 on the rear driving wheels. The opposite runs of the cable are then passed around pulleys 25 secured to the extensions or feet 24 of the anchors. The medial portion of the cable 2 passes around another pulley 26 having a hook 27 which may be slipped over the front axle of the vehicle as shown in Fig. 5.

From the foregoing description taken in connection with the accompanying drawings, it will now be seen that with the apparatus arranged as shown in Fig. 5, upon transmitting motion to the driving wheels of the vehicle, the opposite side portions of the cable 2 will be wound around said drums thereby causing the vehicle to move toward the anchors 20. Thus, the vehicle is enabled to extricate itself from a mired or difficult position under its own power. In bad seasons, when muddy roads may reasonably be expected to be encountered, the drums may be allowed to remain on the hubs of the driving wheels. At other times, said drums may be easily and quickly removed from the wheels and stored in the vehicle. The above advantage of the invention resides in the ease and rapidity with which the device may be applied to and removed from the driving wheel of a vehicle, only a few min-

utes being required for that operation. The device is also compact and of sufficient strength to withstand all stresses which may be imposed thereon.

45

We claim:—

A motor vehicle crab, comprising a drum upon which a cable is adapted to be wound, a flange at the outer side of the body of the drum, said drum having a circular series of openings extending therethrough parallel to the axis of the drum, a circular series of inclined spider arms having outer end portions inserted through the holes in the drum and also having inner end portions parallel to the axis of the drum, intermediate portions of said arms being transversely offset to form the inner flange of the drum, a cushion member adapted to bear against the inner faces of the wheel spokes, clamping members adapted to bear against said cushion member, and having holes to receive the inner end portions of said spider arms, clamping nuts on the inner ends of said spider arms, a wedge shaped block carried by each spider arm and adapted to fit between a pair of the spokes, an abutment ring bearing against the outer face of the drum and formed at points remote from the axis of the drum with holes to receive the outer ends of said spider arms, and clamping nuts threaded on the outer ends of the spider arms and bearing against said abutment ring.

In testimony whereof we affix our signatures in presence of two witnesses.

OTTO N. WAELETTI.
EDWARD F. CHESNEY.
